[57] CLAIM

The ornamental design virtual reality walkie talkie with flip-down eye shield, as shown and described.

DESCRIPTION

FIG. 1 is a top, front, right perspective view of my virtual reality walkie talkie with flip-down eye shield;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a bottom plan view thereof; and,

FIG. 7 is a top plan view thereof.

The broken line showing of human figure is for illustrative purpose only and forms no part of the claim. The antenna in FIGS. 2-5 is shown with an indeterminate length for clarity.
